RAILWAY CAR CONSTRUCTION

Garth G. Gilpin, Riverside, Ill., assignor to Standard Railway Equipment Manufacturing Company, Chicago, Ill., a corporation of Delaware

Application July 18, 1938, Serial No. 219,748

6 Claims. (Cl. 105—380)

The invention relates to railway cars and particularly to cars of the open top type. The side walls of such cars perform two functions; they are the load retaining means and they function as girders which transmit the weight of the lading to the bolsters from which it is transferred to the trucks. The girder consists of upper chord, lower chord, or side sill and stakes and wall plates which function as struts and webs respectively between the chords.

A large number of open top cars have been built with the stakes secured to the outside of the car and the wall sheets secured to the inside surfaces of the stakes. The overall width of such a car is the distance from the outside surface of the stakes on one side of the car to the corresponding surface on the other side of the car. The volume of the car available for lading is the distance between wall sheets. The volume represented by the depth of the stakes on either side of the car is lost; it cannot be used for lading and the cubical capacity cannot be increased because of the restrictions imposed by the exterior stakes.

A common method of overcoming the limitations described above is to build the cars with the wall sheets extending to the maximum width and with the stakes secured to the inside surface thereof. This arrangement utilizes all of the available capacity but has its disadvantages in the corrosion caused by contact with the lading. The stakes then must be of a heavy section to withstand this corroding influence and therein lies another disadvantage in the increased weight and consequently increased non-revenue load.

The stakes used in an open type car must be of very sturdy construction because of the severe service conditions to which they are exposed. As previously stated, they function as struts in a girder to transmit the weight of the lading to the body bolsters. The lading usually hauled in open top cars is of a type which exerts a horizontal pressure, thus loading the stakes as restrained cantilever beams supported rigidly at the lower chord and semi-rigidly to the top chord. In switching cars, it is frequently desirable to move a car by a means adjacent the side of the car, either by a cable and hook fastened to a stake or by a pole braced against a stake. In order to withstand such loading a stake must have sufficient strength to resist lateral deflection or twisting about a vertical axis. Another very severe service condition to which an open top car is subjected is the crushing load applied in dumping or unloading machines. The opera-

tion of these machines is such that the entire car is revolved about a longitudinal axis until the lading discharges through the open top by gravity. The car is held in the machine by a series of blocks on either side of the car, these blocks exerting a crushing force against the sides of the car; thus the stakes must be capable of withstanding a direct compression load and also, since the blocks are not always positioned squarely against the stakes, a partially lateral load which tends to twist the stake about a vertical axis.

In order to obtain the maximum cubical capacity in a car and to protect the stakes from the corroding influence of the lading, cars have been built with the stakes on the outside of the car and with outwardly projecting panels pressed in the wall sheets. These panels lie substantially in the plane of the outer surface of the stakes and extend substantially between the stakes and between the upper and lower chords. They are connected to the margins of the sheets by sloping webs. It is an object of this invention to further increase the cubical capacity of the car by increasing the width of the outwardly projecting panels; that is, increasing their dimension longitudinally of the car.

It is another object of the invention to increase the capacity of the car by extending the panels of adjacent sheets closer to each other by decreasing the space required between the panels for the stake. This invention applies principally to a stake which is riveted to the sheets along the longitudinal line of the stake. It is a further object of the invention, by positioning the rivets in offsets of the stake, preferably staggered, to decrease the space required for the stake without decreasing the strength of the stake.

In the drawing:

Fig. 1 is a partial side elevation of an open top railway car.

Figs. 2, 3 and 4 are sections on lines 2—2, 3—3 and 4—4, respectively, of Fig. 1.

Figs. 5, 6, 7 and 8 illustrate alternate constructions.

In Figs. 1 and 2, the usual parts of an open top railway car are shown, such as upper chord 2; lower chord or side sill 3; a cross member of the underframe 4; a stake 5 and portions of wall sheets 6 on either side of the stake 5. The wall sheets 6 have pressed therein outwardly projecting panels 7 connected by webs 8 to the marginal portions 9 which lie substantially in the plane of the upper (2) and lower (3) chords. 55

The panels extend effectively to the stake 5 and between the chords (2 and 3).

The stake 5 is substantially channel shaped and comprises connected webs 15, each web having a flange 16 projecting outwardly therefrom, as shown in Figs. 3 and 4. The webs 15 preferably diverge toward the wall but have pressed therein inwardly offset portions 17 whose walls 18 are substantially normal to the plane of the wall sheet 6. The flange 16 thus has parts 19 adjacent the offset portions 17 to provide sufficient space for a die to form the heads on the rivets 20. The offset portions 17 in the opposite webs 15 are preferably staggered relative to each other so that an offset portion in one web is not adjacent an offset portion in the opposite web.

The staggering of the offset portions 17 makes it possible to increase the cubical capacity of the car by moving the webs 8 (see Figs. 3 and 4) close to each other without weakening the stake 5. If the width of a stake be defined as the distance between the web-like portions shown cross-hatched, the minimum width at any section of the stake is the distance between the web 15 and the offset portion 17 of the opposite web. If it is assumed that the offset portions 17 are opposite each other, the walls 18 become relatively close to each other, thus weakening the stake 5. To increase the distance between walls 18 is to decrease the width of the panels 7 and consequently decrease the cubical capacity of the car. If the offset portions 17 are staggered, however, the effective width of the stake becomes the distance between a web 15 and a wall 18 of an offset portion 17 since there is no section of the stake of less width than this. It is, therefore, an object of this invention to increase the cubical capacity of the car by staggering the rivets, thus decreasing the space required for the stake.

Fig. 5 shows a modified construction in which the wall sheets 6 are not overlapped. A splice plate is riveted to the inside of the wall sheets 6 to reinforce the stake 5 against spreading and to protect it from the corroding influence of the lading. Otherwise, the stake 5 is substantially similar to that shown in Figs. 1 to 4.

Figs. 6 and 7 show a modification of the stake wherein the connected webs 30 are not substantially flanged except at the offset portions 31. The webs 30 are provided with small flanges 32 to increase their bearing area on the wall sheet. The wall sheets 6 are secured to the stake 5 by rivets 33 through the parts 34. The parts 34 exist only adjacent the offset portions 31 and are entirely within the boundary of the webs, thus making it possible to extend the webs 8 of the wall sheet to closely adjacent the webs 30 of the stake 5. Fig. 6 differs from Fig. 7 only in that the webs 30 of the former are flared, while those of the latter are substantially normal to the wall sheets.

Fig. 8 is similar to Figs. 3 and 4 in that the webs 15 are provided with relatively narrow flanges 16 which have relatively wide parts 19 adjacent the offset portions 17 to provide space for rivets. In the modification shown in Fig. 8, however, the webs 15 are normal to the plane of the wall sheets, while in Figs. 3 and 4, the webs 15 are flared.

The accompanying drawing illustrates the preferred form of the invention, though it is to be understood that the invention is not limited to the exact details of construction shown and described, as it is obvious that various modifications

thereof within the scope of the claims, will occur to persons skilled in the art.

I claim:

1. In an open top railway car having an upper chord, and a lower chord, a substantially channel shaped stake extending between and secured to said chords, said stake comprising spaced apart connected webs, a pair of wall sheets extending between and secured to said chords to form a load retaining means therebetween, each of said sheets having an outwardly projecting panel formed therein, said panel extending substantially to said stake and between said chords to increase the cubical capacity of the car, the webs of said stakes having inwardly offset portions to provide parts for attachment of said stake to said wall sheets, and rivets forming means for said attachment, the offset portions in opposite webs being staggered relative to each other, whereby said panels may extend to closely adjacent said webs and whereby the effective width of said stake is the distance between a web and an offset portion of the opposite web.

2. In an open top railway car having an upper chord, and a lower chord, a substantially channel shaped stake extending between and secured to said chords, said stake comprising spaced apart connected webs, each web having a relatively small outwardly projecting flange, a pair of wall sheets extending between and secured to said chords to form a load retaining means therebetween, each of said sheets having an outwardly projecting panel formed therein, said panel extending substantially to said stake and between said chords to increase the cubical capacity of the car, the webs of said stakes having inwardly offset portions to provide relatively large outwardly projecting flanges for attachment of said stake to said wall sheets, and rivets forming means for said attachment, the offset portions in opposite webs being staggered relative to each other, whereby said panels may extend to closely adjacent said webs and whereby the effective width of said stake is the distance between a web and an offset portion of the opposite web.

3. In an open top railway car having an upper chord, and a lower chord, a substantially channel shaped stake extending between and secured to said chords, said stake comprising flared connected webs, a pair of wall sheets extending between and secured to said chords to form a load retaining means therebetween, each of said sheets having an outwardly projecting panel formed therein, said panel extending substantially to said stake and between said chords to increase the cubical capacity of the car, the webs of said stakes having inwardly offset portions substantially normal to the plane of said wall sheets to provide parts for attachment of said stake to said wall sheets, and rivets forming means for said attachment, the offset portions in opposite webs being staggered relative to each other, whereby said panels may extend to closely adjacent said webs and whereby the effective width of said stake is the distance between a web and an offset portion of the opposite web.

4. In an open top railway car having an upper chord, and a lower chord, a substantially channel shaped stake extending between and secured to said chords, said stake comprising flared connected webs, each web having a relatively small outwardly projecting flange, a pair of wall sheets extending between and secured to said chords to form a load retaining means therebetween, each of said sheets having an outwardly projecting

panel formed therein, said panel extending substantially to said stake and between said chords to increase the cubical capacity of the car, the webs of said stakes having inwardly offset portions substantially normal to the plane of said wall sheets to provide relatively large outwardly projecting flanges for attachment of said stake to said wall sheets, and rivets forming means for said attachment, the offset portions in opposite webs being staggered relative to each other, whereby said panels may extend to closely adjacent said webs and whereby the effective width of said stake is the distance between a web and an offset portion of the opposite web.

5. In a railway car having upper and lower chords, a stake extending therebetween and secured thereto, a wall sheet disposed on each side of said stake in substantially the same plane, means to secure marginal portions of said sheets

to said stake, said sheets having formed therein outwardly projecting panels adjacent said stake to increase the cubical capacity of the car, and staggered inwardly projecting offset portions in said stake in which said means are positioned for the purpose specified.

6. In a railway car having upper and lower chords, a stake extending therebetween and secured thereto and having oppositely projecting flanges, a wall sheet disposed on each side of said stake in substantially the same plane, means to secure marginal portions of said sheets to said flanges, said sheets having formed therein outwardly projecting panels adjacent said stake to increase the cubical capacity of the car, and staggered inwardly projecting offset portions in said stake in which said means are positioned for the purpose specified.

GARTH G. GILPIN.
